US0D1095592S

(12) **United States Design Patent** (10) **Patent No.:** **US D1,095,592 S**
(45) **Date of Patent:** **** Sep. 30, 2025**

(54) **DISPLAY SCREEN OR PORTION THEREOF
WITH GRAPHICAL USER INTERFACE**

(71) Applicant: **Brainlab AG**, Munich (DE)

(72) Inventor: **Michael Rex**, Munich (DE)

(73) Assignee: **Brainlab SE**, Munich (DE)

(**) Term: **15 Years**

(21) Appl. No.: **29/938,736**

(22) Filed: **Apr. 23, 2024**

Related U.S. Application Data

(62) Division of application No. 29/919,170, filed on Dec. 1, 2023, now Pat. No. Des. 1,029,876, which is a division of application No. 29/771,987, filed on Feb. 26, 2021, now Pat. No. Des. 1,013,702.

CLAIM

The ornamental design for a display screen or portion thereof with graphical user interface as shown and described.

DESCRIPTION

The FIGURE is a front view of a display screen or portion thereof with a graphical user interface showing my new design.

The outermost broken lines show a display screen or portion thereof, and form no part of the claimed design. The other broken lines show portions of the graphical user interface that form no part of the claimed design.

1 Claim, 1 Drawing Sheet
